UNITED STATES PATENT OFFICE.

PETER S. STEENSTRUP, OF NEWARK, NEW JERSEY, ASSIGNOR TO HYATT ROLLER BEARING COMPANY, OF HARRISON, NEW JERSEY, A CORPORATION OF NEW JERSEY.

ROLL-MOUNTING FOR ROLLER-BEARINGS.

No. 859,347.

Specification of Letters Patent.

Patented July 9, 1907.

Application filed December 8, 1904. Renewed December 12, 1906. Serial No. 347,613.

To all whom it may concern:

Be it known that I, PETER S. STEENSTRUP, a citizen of the United States, residing at 83 Ridgewood avenue, Newark, county of Essex, State of New Jersey, have 5 invented certain new and useful Improvements in Roll-Mounting for Roller-Bearings, fully described and represented in the following specification and the accompanying drawings, forming a part of the same.

The objects of the present invention are partly, to 10 furnish a cheap construction for the roller guide used in bearings having anti-friction rolls, and partly, to hold the series of rolls together when removed from the bearing, and these objects are attained by forming sheet metal heads with mortises stamped at suitable intervals, and connecting the same by tie-bars stamped with integral tenons adapted to fit the mortises; to be riveted therein.

The invention also includes a means of pivoting the rolls upon the roller guide by forming integral bosses 20 upon the sheet metal heads. The bosses are arranged upon the heads in two groups which are separated by spaces greater than the spaces between the bosses; so that the rolls may all be held close to one another excepting where the tie-bars are inserted between the groups. 25 The heads are preferably formed with rectangular holes at opposite sides of the center between the groups to receive squared ends upon the tie-bars, and it is also preferable to flare the holes outwardly and to form squared tenons upon the tie-bars which can be riveted in the holes. When the tie-bars are thus secured to the heads, the bosses upon the heads hold the rolls in a fixed relation to one another, so as to maintain their parallelism when in operation. The tie-bars being made of sheet-metal have a much greater width than 30 thickness, and they are extended radially in the direction of their width, so as to consume very little space in the circuit of the heads, and separate the adjacent rolls as little as possible. The heads and tie-bars form a cage which enables the whole series to be handled as a unit in packing, in transportation, and in applying them to or removing them from the casing of the roller bearing. The heads are of circular form so that the shaft requires to be inserted endwise into the set of rolls through the apertures in the heads.

40 In the annexed drawing, Figure 1 is an end view of the set of rolls with the cage which is formed of the heads and tie-bars. Fig. 2 is a side view of the same showing the nearer tie-bar between the two groups of rolls. Fig. 3 is a longitudinal section of the cage on line 45 3, 3, in Fig. 1; and Fig. 4 is a plan of one of the tie-bars.

Fig. 1 shows a set of eight rolls divided into two groups, the rolls *a* in the upper group being shown formed of spiral springs which possess a central hole *b* throughout their length, and the rolls *a'* in the lower group being solid with suitable sockets *b'* in their oppo-

site ends. The invention is applicable to either kind of rolls.

The heads *c* are shown of sheet-metal with two groups of bosses *d* and *d'* stamped upon their inner sides of suitable size to fit loosely in the sockets *b* and in the 60 holes *b* of the rolls which form corresponding sockets.

In Fig. 2, an end of one of the rolls *a* and of the rolls *a'* is shown in section to exhibit the penetration of the bosses into the sockets of the rolls.

The bosses *d* and *d'* are formed at such a distance apart 65 that the rolls just clear one another, but the groups of bosses *d* and *d'* are separated more widely, so as to admit tie-bars *e* between the two groups of rolls.

Rectangular holes or mortises *f* are shown in the heads 70 between the groups, at opposite sides of the center of the head, and are flared outwardly as shown in Fig. 3, and the tie-bars *e* have squared tenons *g* upon their ends fitted to the holes *f*, and secured therein by riveting the outer ends of the tenons upon the outer side of the head.

The tie-bars with their square tenons are readily 75 formed at a single operation by stamping from sheet metal with a suitable punch and die, and such tie-bars are thus much cheaper than those formed of round rods with tenons milled upon the ends to form a shoulder. 80 The holes are so disposed in the heads as to hold the breadth of the tie-bars radially; that is, at right angles to the periphery of the head, and the tie-bars thus occupy the least possible space between the adjacent rolls.

The riveting of the tenons swells their outer ends 85 to fill the flared holes, and the heads are thus held together with sufficient strength. The length of the tie-bars is made such that the ends of the rolls slightly clear the inner sides of the heads, and the rolls are thus 90 adapted to turn freely upon the bosses, while the heads and tie-bars hold all the rolls in place, so that when removed from the bearing they are readily handled as a unit.

The use of sheet metal, exclusively, furnishes a very 95 cheap construction for the heads and tie-bars, and as roller guides are often made without bosses to engage the ends of the rolls, the construction may therefore be employed in making such roller guides.

The parts of the cage are formed wholly of sheet- 100 metal, which are entirely shaped by stamping dies, and the structure is thus cheap to manufacture while very durable in its character.

I am aware that heads for roller guides have been constructed with a stud to support each guide, but such 105 studs are commonly inserted in the heads, which requires accurate drilling of the heads and fitting of the studs, and necessitates the making and use of many pieces for each guide. By the use of sheet metal which is rolled smoothly in the process of manufacture, the 110

heads and stud constitute only a single piece, and I am enabled to stamp the studs directly upon the heads at a single operation, thus forming them integral with the heads and of suitable shape and finish to guide the rolls, 5. without any machine work. I do not therefore claim broadly a roller guide having studs to fit the ends of rolls, but the sheet metal construction which is described herein.

Having thus set forth the nature of the invention 10 what is claimed herein is:

The roll-mounting, for roller bearings for rolls arranged in close proximity and divided into two groups, comprising two annular sheet-metal heads *c* each having an even number of hollow bosses *d* and *d'* upon its inner face and

the bosses arranged in two groups at opposite sides of the 15 center, with greater spaces between the groups than between the bosses in the groups, and the heads having the rectangular mortises *f* therethrough at opposite sides of the center midway between the groups, the series of rolls *a* having sockets *b'* in their opposite ends fitted in two 20 groups to the bosses *d* and *d'*, and the flat sheet-metal tapers *e* having flat rectangular tenons *g* fitted to the rectangular mortises *f* and riveted therein, and thereby held radially between the two groups of rolls, substantially as herein set forth.

In testimony whereof I have hereunto set my hand in the presence of two subscribing witnesses:

PETER S. STEENSTRUP.
